ATTYS

UNITED STATES PATENT OFFICE.

ALBERT J. HORTON, OF WHITE PLAINS, NEW YORK, ASSIGNOR TO R. HOE & CO., INC., OF NEW YORK, N. Y., A CORPORATION OF NEW YORK.

PLATE-PRINTING MACHINE.

Application filed October 22, 1927. Serial No. 227,914.

This invention relates to certain improvements in controlling devices for controlling the movements of the plate supporting beds or planks in plate printing machines. 5 In certain classes of plate printing machines, the engraved plates are supported on beds or planks which are given a traveling movement around a rectangular frame under suitable inking, wiping, and impression mechanisms, these mechanisms being conveniently arranged on different sides of the frame. In its traveling movement around the frame, the direction of the plank is changed, these movements being at right angles to each other where the plank goes around the corners. These planks and the mechanisms by which they are operated are heavy and the change in the direction of movement is apt to produce a jar, which 10 causes wear of the parts, is noisy, and is objectionable for various other reasons. Furthermore, the planks are apt to turn improperly in going around the corners, with the result that they do not properly engage 15 the guides by which their straight line movements are controlled.

It is the especial object of the present invention to provide a simple and effective construction for controlling the plank or bed as it moves around the corners during its traveling movement in the machine which will act to properly direct the plank so that it will be lined up with its guides, and in which the jar or chattering of the bed in 20 going around the corners is eliminated, these controlling means being of such character and so positioned as not to interfere with the operation of the driving mechanism for the bed or plank.

40 It is a further object of the invention to provide such means which may be readily installed in a machine without requiring changing or re-arrangement of the mechanism.

45 With these and other objects not specifically referred to in view, the invention consists in certain novel parts, arrangements and combinations which will be fully described in detail in the accompanying draw-

ings and the novel features pointed out in 50 the claims hereunto annexed.

In these drawings,

Figure 1 is a plan view, partly broken away, of one corner of a power plate machine illustrating the invention and showing the 55 bed or plank approaching a corner, and

Figure 2 is a sectional view of the construction shown in Figure 1, the section being taken on line 2—2 of that figure and looking in the direction of arrow 2. 60

Referring now to these drawings, there has been illustrated one corner of a power plate machine showing the improved plank controlling device, it being understood that the construction is duplicated at each corner 65 of the press. In the construction shown there is provided suitable frame-work in the form of a rectangle, two sides, 1, 2, of which are illustrated. This framework may be of any suitable character, but is preferably 70 formed with a shoulder 3 and a ledge 4, which form an outside guide for the plate bed or plank 5. Inner guides 6 may be provided, the plate, in its straight line movements, being guided by the guides 6 and the shoulder 3. The guides 6 and the frames 75 1, 2 at the corners are curved, as indicated at 7, the plank moving around these curved portions during its traveling movement.

The plank is driven in any suitable manner and, in the particular construction shown, there is provided a vertical shaft 8, driven from any suitable source of power, supported at its upper end in a hub 9 formed in a web 10, which may be part of 80 the framing 1, 2, before referred to. This shaft, at its upper end, is provided with a driving sprocket 11 over which passes a driving chain 12 which carries a driving pin 13 which engages in a socket 14 formed on 85 the under side of the plank 5. In accordance with the invention, means are provided for controlling the movement of the plank as it passes around the corners of the frame and to cause the plank to be properly positioned with respect to the side guides which engage it after it has made the turn. 90

While the specific arrangement of these

controlling means may be somewhat varied, in the particular construction shown the plank on its under side is provided at or near each corner with a pin 15. Cooperating with two of these pins is a pair of guiding members having curved controlling surfaces, these members being arranged to engage the pins in opposite corners of the plank. While these controlling members 10 may be of various forms, in the particular construction shown they preferably will be rotatable and are shown in the form of disc wheels 16, 17. The wheel 16 is rotatably carried on a spindle 18 mounted in a web 19 of the frame, and the wheel 17 is carried on a spindle 20 supported in a web 21 of the main frame, these wheels being arranged, as shown, so that they are on the same side of the pins, that is, at the right of the pins, 15 as shown in Figure 1. While the pins have been shown as carried by the bed or plank and the wheels as supported in the webs, it will be understood that this arrangement 20 could be readily reversed.

25 The parts are arranged so that the distance from the center of the controlling disc 16 to the center of the pins 15 is the same as the distance from the center of the shaft 8 to the pitch line of the sprocket 11. With 30 this arrangement, assuming the bed to be moving in the direction of arrow 1 of Figure 1, as the pin 13, which drives the bed or plank, moves around this sprocket, the pins 15 will likewise pass around the discs 16, 17.

35 Any tendency of the bed or plank to turn or move on its driving pin will result in the pressing of one of the pins 15 against the disc which it engages, and any tendency of the plank to turn in the other direction will 40 result in the other pin pressing against its wheel. Thus the plank is properly guided as it passes around the corners of the frame, and any liability to get out of line or to chatter is overcome. The two pins indicated at 15' in the opposite corners of the 45 plate, it is understood, will engage discs at the next corner, similar to discs 16, 17, so that the plank is properly guided throughout its entire travel around the frame.

50 While the invention has been shown and described in its preferred forms, it will be understood that various changes may be made in the form and arrangement of the parts without departing from the invention 55 as defined in the appended claims.

What I claim is:

1. In a plate printing machine, the combination with the frame, of a traveling bed or plank, projections near opposite corners 60 of the plank, and discs on the frame engaged by the projections as the plank passes around a corner of the frame.

2. In a plate printing machine, the combination with the frame, of a traveling bed

or plank, pins near opposite corners of the 65 plank, and discs on the frame engaged by the pins as the plank passes around a corner of the frame.

3. In a plate printing machine, the combination with the frame, of a traveling bed 70 or plank, diagonally arranged pins on the plank, and discs rotatably mounted on the frame engaged by the pins as the plank passes around the corner of the frame.

4. In a plate printing machine, the combination with the frame, of a traveling bed 75 or plank, a sprocket chain for driving the plank, pins on the plank, and discs on the frame engaged by the pins, the distance between the centers of the discs and pins being 80 the same as the distance from the center of the sprocket to its pitch line.

5. In a plate printing machine, the combination with the frame, of a traveling bed 85 or plank, pins on the plank, and discs on the frame arranged on the same side of the pins and engaged by the pins as the plank passes around the corners of the frame.

6. In a plate printing machine, the combination with the frame, of a traveling bed 90 or plank, pins on the plank, and oppositely disposed guides having curved surfaces on the frame arranged on the same side of the pins and engaged by the pins during the whole traveling movement of the plank 95 around the corners of the frame, so that the plank is held against swinging in either direction during such movement.

7. In a plate printing machine, the combination with the frame, of a traveling bed 100 or plank, discs on the frame, and depending pins on the plank engaging the discs during the whole movement of the plank around the corners of the frame.

8. In a plate printing machine, the combination with the frame, of a traveling bed 105 or plank, a chain for driving the plank, cooperating pins and curved guides on the plank and frame located below the plank 110 and outside the chain, for guiding the plank as it passes around the corners of the frame.

9. In a plate printing machine, the combination with the frame, of a traveling bed 115 or plank, projections arranged on the plank diametrically opposite each other, and oppositely disposed abutments on the frame engaged by the projections during the whole traveling movement of the plank around a corner of the frame, so that the plank is held against swinging in either direction 120 during such movement.

10. In a plate printing machine, the combination with the frame, of a traveling bed 125 or plank, projections arranged on the plank diametrically opposite each other, and oppositely disposed rotary abutments on the frame engaged by the projections during the whole traveling movement of the plank

around a corner of the frame, so that the plank is held against swinging in either direction during such movement.

11. In a plate printing machine, the combination with the frame, of a traveling bed or plank, projections arranged on the plank diametrically opposite each other, and oppositely disposed abutments on the frame en-

gaged by the projections as the plank passes around a corner of the frame, said projections and abutments being located below the plank. ¹⁰

In testimony whereof, I have hereunto set my hand.

ALBERT J. HORTON.
